UNITED STATES PATENT OFFICE.

GEORGE H. COVE, OF WHITESTONE, NEW YORK, ASSIGNOR TO HENRY BOHNE AND HENRY STEINER, BOTH OF WHITESTONE, NEW YORK, COPARTNERS DOING BUSINESS AS STEINER NOVELTY WORKS.

DESIGN FOR TOY WINDMILL AND SEESAW.

49,879.

Specification for Design.

Patented Nov. 14, 1916.

Application filed May 17, 1916. Serial No. 98,236. Term of patent 7 years.

To all whom it may concern:

Be it known that I, GEORGE H. COVE, a subject of the Kingdom of Great Britain and Ireland, residing at Whitestone, in the county of Queens and State of New York, have invented a new, original, and ornamental Design for a Toy Windmill and Seesaw, of which the following is a specification, reference being had to the drawing filed by me with the original specification May 17, 1916, forming part thereof and hereof.

The figure is a view in elevation of a toy windmill and see-saw, showing my new design.

I claim:

The ornamental design for a toy windmill and see-saw, as shown.

GEORGE H. COVE.
